UNITED STATES PATENT OFFICE

113,727

DESIGN FOR A COMBINED RADIO TUNING MOTOR AND MOUNTING PANEL

Edward L. Barrett, La Grange, Ill., assignor to
Utah Radio Products Company, Chicago, Ill.,
a corporation of Illinois

Application December 24, 1937, Serial No. 73,850

Term of patent 7 years

To all whom it may concern:

Be it known that I, Edward L. Barrett, a citizen of the United States, residing at La Grange, in the county of Cook and State of Illinois, have invented a new, original, and ornamental Design for a Combined Radio Tuning Motor and Mounting Panel, of which the following is a specification, reference being had to the accompanying drawing, forming part thereof.

Fig. 1 is a side elevation of a combined radio tuning motor and mounting panel embodying the features of the invention.

Fig. 2 is a perspective view of the same.

Fig. 3 is an elevational view of the side opposite to that shown in Fig. 1.

My design is characterized by the provision of an elongated flat rectangular panel through which one end of the motor projects for a short distance and with the panel presenting a smooth generally imperforate surface hiding the body of the motor when the combined structure is viewed from the panel side as in Fig. 1.

I claim:

The ornamental design for a combined radio tuning motor and mounting panel, substantially as shown and described.

EDWARD L. BARRETT.
